ELECTRICAL GUITAR

Charles E. Moore, R.F.D. 1, Highway 32W.,
Winchester, Ind. 47394

Filed Oct. 31, 1969, Ser. No. 19,865

Term of patent 14 years

Int. Cl. D17—03

U.S. Cl. D56—1

FIG. 1 is a top plan view of an electrical guitar, shown without the strings attached thereto, showing my new design;

FIG. 2 is a front elevational view thereof;

FIG. 3 is a side elevational view thereof;

FIG. 4 is an end view thereof, showing the appearance of one end thereof;

FIG. 5 is a perspective view thereof, showing the appearance of the other end thereof; and

FIG. 6 is a sectional view thereof, taken substantially along the section line 6—6 of FIG. 1.

I claim:

The ornamental design for electrical guitar, as shown and described.
